(74) Attorney, Agent, or Firm — Rothwell, Figg, Ernst & Manbeck, P.C.

CLAIM

The ornamental design for a bag, as shown and described.

DESCRIPTION

FIG. 1 is a front left perspective view of a bag showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a front left perspective view in open position thereof;

FIG. 9 is a front view in open position thereof;

FIG. 10 is a rear view in open position thereof;

FIG. 11 is a left side view in open position thereof;

FIG. 12 is a right side view in open position thereof;

FIG. 13 is a top view in open position thereof; and,

FIG. 14 is a bottom view thereof.

The portions of the bag shown in broken lines represent thread stitching and do form a part of the claimed design.

1 Claim, 14 Drawing Sheets
